INVENTOR

UNITED STATES PATENT OFFICE

FRANK T. POWERS, OF DOUGLASTON, NEW YORK

ETCHING MACHINE

Application filed September 15, 1926. Serial No. 135,696.

The invention relates to improvements in apparatus intended for use in the preparation of the surfaces of metal plates used in printing by the chemical action thereon of an etching fluid. Apparatus of this character is useful in certain stages of the preparation of photo-mechanical printing plates known as "half-tone plates" or "line cuts", and for other purposes.

10 One object of my invention is to enable the operator to etch a printing plate at one continuous operation for each stage or "bite," as it is called, of the etching process without the necessity of stopping or interrupting the etching process to alter the position of the plate or to remove from its surface, by means of a brush or otherwise, the oxide or residue left on the plate by the etching process, which it is commonly necessary to do with other forms 20 of etching apparatus now in use.

Another object of my invention is to provide means for producing an etching action of such uniformity over the entire surface of the plate that what the printer calls "color 25 values" in the half-tones and shadows will be truly retained and at the same time give such ample depth of etching of the plate as will yield satisfactory printing quality.

It is also important that the etching process vertically down the sides of the lines or dots perpendicular to the surface of the plate without undercutting or shoulderering. These highly desirable results are attained by my invention to a degree far in excess of those 35 produced by machines heretofore in use for this purpose.

Another advantage possessed by this invention over other forms of etchers using rotating sprayers lies in the fact that with a 40 sprayer of the form described the plate may be etched, either in a substantially horizontal position, face downward, attached to the underside of the cover of the machine, or in a substantially vertical position in the path of the spray. This feature enables the operator to etch plates in either position or to etch plates placed in both positions simultaneously.

Still another important advantage is the 50 ability to produce sprays of varying charac-

teristics, such as fineness of particles, volume of fluid sprayed and velocity of travel of the particles.

The various novel features of my invention will be more fully set forth and illustrated in the accompanying description and drawings.

In the drawings like numbers are used to indicate the same or similar parts.

Figure I is a general assembled view of the 60 apparatus with portions indicated as cut away to give a clearer view of interior elements.

Figure II shows a side view of one form of the spraying device.

Figure III shows an end view of the device 65 shown in Figure II.

Figure IV is a side view, in perspective, of one special form of plate or element for the spray producing unit.

Referring more in detail to the drawings—in Figure I, 1 indicates an acid-proof liquid receptacle, within which is suitably mounted a rotating spraying device 2 fixed to a shaft 3. Suitable means, not shown in the drawing, are provided for rotating shaft 3 at suitable speed or at various speeds. On the underside of the cover 1^a of the receptacle 1 are provided means for holding the plate 5 or other object to be etched. In the drawing 75 slotted cleats 6, 6 are shown for the convenient reception of plates to be etched, but these means may be varied to suit the form and size of article to be etched. On one side of the interior of the receptacle, the side opposite to that near which the rotating member 2 is mounted, is provided a ledge 7 or equivalent support upon which may be placed a plate 8 to be etched.

In Figure II, which shows a side view of 90 the rotating member, 9 indicates plates or elements of suitable material mounted on a shaft 3, with spacers 10 alternating with the plates or elements 9. Said spacers being of suitable thickness to hold the said plates at a suitable 95 distance apart on the shaft 3. On either side of the aggregation of alternate plates 9 and spacers 10 are nuts 11 whose interior threads engage mating threads 12, on the shaft 3, and by means of these nuts the plates and spacers 100

are held firmly together on the shaft. A spline or key 13 engaging both the shaft and the plates and spacers, prevents the plates and spacers from rotating on the shaft.

It must be understood that there are many possible variations from the form and construction of the apparatus shown in the drawings and that I do not intend to limit myself to this particular form or design or construction or combination of parts so long as the spirit of the invention is adhered to.

Having described the drawings showing one of the preferred forms of the invention, I will now describe the method of its operation.

Before starting the operation liquid receptacle 1 is filled with a suitable etching fluid to a point below the shaft 3. The level of this etching fluid is such that the corners of the plates or elements 9 of the rotating spraying device 2 will dip into the fluid and pick up on their sides and edges a portion of the liquid while passing through it, only to throw off the liquid by centrifugal force as that portion of the spraying element passes over the top of the shaft and re-enters the liquid on the other side.

The metal plate or plates to be etched are attached by means of the slots 6 to the under side of the cover 4 or the plate may be stood up in a nearly vertical position inside the tank leaning against the front of the tank and supported by the ledge 7. This ability to etch two or more plates, one attached to the cover of the apparatus and at the same time etch one or more plates standing in the tank is one of the important advantages of my invention not possessed by other machines now in use for this purpose. Having closed the cover, the power is applied to the shaft 3 which results in the rotating elements of the sprayer picking up the etching fluid and throwing it in fine drops against the plates to be etched. While these rotating elements pass through the fluid the corners of elements beat up the liquid and in a very short time produce an aerated fluid or frothy emulsion which is found to be very desirable and effective as an etching medium. This aerating effect is produced to a marked degree by elements of a rectangular shape or by elements of other than circular form. It has been found that circular or cylindrical elements in this rotating member or sprayer do not produce the much desired results on the plate being etched that elements or sections of polygonal shapes produce.

At the expiration of a definite period of time which has been predetermined by experiment or experience the power is shut off, the sprayer comes to a standstill and the finished plates are removed.

It has been found with certain grades of etching a more violent spraying action is advantageous. In order to increase the quantity of etching fluid thrown against the

object being etched the level of the liquid in the receptacle may be raised. In some cases a very fine spray is desired. To accomplish this the speed of rotation of the spraying element is increased. Conversely, if spray particles of larger sizes are desired, the speed of rotation of the spraying element is reduced.

When a still greater quantity of etching fluid is desired to be projected against the object to be etched then elements of some such form as that shown in Figure IV are used instead of the form shown in Figures II and III.

Obviously a great variety of forms of vanes or buckets could be devised which would serve the purpose of increasing the amount of etching fluid which the revolving polygonal element will pick up as it revolves in the etching fluid. I do not confine myself to any particular form or design. One advantage possessed by the form of bucket indicated in the drawing lies in the fact that when the element is rotated in the direction indicated by the arrow, a portion of the etching fluid picked up by the forward outer tip of the vanes or buckets will, by reason of its inertia, flow over the entire inner advancing faces 15 of the buckets 14, and pass around and beyond the inner portion of the bucket between the bucket and the shaft 3, only to be picked up in turn by the succeeding bucket and projected therefrom, by centrifugal force, against the object to be etched.

In the foregoing description the rotating member, also referred to as the sprayer, is described as composed of alternate plates and spacers. This is the preferred construction but I find that variations from this form are also very effective. This paddle wheel may be solid instead of laminated, and the cross section may vary from the square form shown in the drawings as the preferred construction. The cross section of this rotating member may be triangular or pentagonal, or hexagonal or any other angular form, either regular or irregular. The essential thing is to provide a many-sided paddle wheel the corners of which will beat up the etching fluid to a froth and mix air with the liquid, while at the same time it throws drops of the fluid forcibly against the surface of the metal plate being etched.

I am aware that etching machines having paddle wheels of various forms have been and are in use and that in etching machines of this general character some etch the plate in a horizontal, face-down position and others in a vertical position. I am therefore limiting my claims to those features which I believe to be new and novel.

Having described my invention and its method of operation, I will now state what I claim to be novel and new upon which I desire to secure Letters Patent:

1. A device for spraying a fluid comprising

ing a rotatable member composed of thin elements having the form of a rectilinear polygon mounted at spaced distances apart on a shaft.

5 2. A device for spraying a fluid comprising a rotatable member composed of thin elements having the form of a regular rectilinear polygon mounted at spaced distances apart on a shaft.

10 3. A device for spraying a fluid comprising a rotatable member composed of thin elements having the form of a regular, equilateral rectilinear polygon mounted at spaced distances apart on a shaft.

15 4. A device for use in an etching machine for spraying the etching fluid, comprising a rotatable member composed of thin elements having polygonal form mounted at equal distances apart on a shaft.

20 5. A spraying device for use in an etching machine, comprising a rotatable member composed of thin elements of rectangular form mounted on a shaft.

25 6. A spraying device for use in an etching machine, comprising a rotatable member composed of a shaft upon which is mounted elements of polygonal form, having at corners of the elements vanes adapted to dip into, pick up and project the etching fluid.

30 Signed at Douglaston, in the county of Queens, city and State of New York, this tenth day of September, A. D. 1926.
